United States Patent

Des. 241,187
Patented Aug. 31, 1976

241,187

APRON

Doris Brosk, 150 E. 69th St.,
New York, N.Y. 10021

Filed Dec. 19, 1974, Ser. No. 534,572

Term of patent 14 years

Int. Cl. D2—02

U.S. Cl. D2—227

The figure is a front perspective view of an apron showing my new design with the applique in opened condition. The rear of the apron is identical to the front except for the omission of the ornamentation on the body of the apron.

I claim:

The ornamental design for an apron, as shown and described.
